PRINTER'S LINE-UP TABLE

Filed June 10, 1925

2 Sheets-Sheet 2

UNITED STATES PATENT OFFICE.

JAMES WEST, OF JAMAICA PLAIN, BOSTON, MASSACHUSETTS, ASSIGNOR, BY MESNE ASSIGNMENTS, TO NATIONAL PRINTERS' SUPPLY CO., A CORPORATION OF MASSACHUSETTS.

PRINTER'S LINE-UP TABLE.

Application filed June 10, 1925. Serial No. 36,256.

My invention relates to printers' line-up and register tables adapted for inspecting proof sheets to determine the alinement thereof, and for lining up blank sheets or preparing strike sheets, etc., and its object is to improve and simplify devices of this kind in the manner hereinafter more fully set forth.

My invention comprises a table having a transparent top with illuminating devices arranged under the same so that proof sheets placed on said table can be inspected for precise alinement, a plurality of sheet-stops arranged at the forward edge of the table, with each of which stops a sheet gripper is associated, and two alining bars arranged at right angles to each other and mounted for transverse and longitudinal movement across the table without change in their angular relation, one of said bars being disposed parallel to a line connecting the forward ends of said stops. Preferably the sheet-stops are maintained in contact with the table by resilient means which co-operate with the sheet grippers to raise the same above the table, a cam lever or the like being provided for depressing the gripper after a sheet has been placed on the table.

My invention comprises also an arrangement of cams or other suitable members whereby each of said bars may be elevated above said table by moving the same at right angles to its direction of movement across the table.

A marking device may be mounted on each bar and arranged for movement longitudinally of the same, means being provided for adjusting such device vertically.

An illustrative embodiment of my invention is shown in the drawings accompanying and forming a part of this specification in which—

Figure 1 is a plan view of a printer's line-up and register table constructed in accordance with my invention;

Fig. 2 is a front elevation;

Fig. 3 is a fragmentary side elevation on an enlarged scale;

Fig. 4 is a fragmentary rear elevation;

Fig. 5 is an elevation of the side gage;

Fig. 6 is a plan view of said side gage;

Fig. 7 is a side view of my improved combined sheet-stop and gripper;

Fig. 8 is a plan view of said sheet-stop and gripper;

Fig. 9 is an end view of said combined sheet-stop and gripper;

Fig. 10 is a front elevation of a marking device that may be used with my improved line-up table;

Fig. 11 is a transverse vertical section of said marking device taken on the line 11—11 of Fig. 10;

Fig. 12 is a plan view of said marking device;

Fig. 13 is a front elevation of a modified form of said marking device;

Fig. 14 is a plan view of the marking device shown in Fig. 13.

In the particular drawings selected for more fully disclosing the principle of my invention 20 represents a table having a transparent top 21 illuminated from beneath by the electric lamps 22, said top being designed to receive proof sheets of large size 75 on which are arranged series of printed units such as a number of pages of a book which are to be printed simultaneously and which it is required to place in precise alinement with one another so that when cut and trimmed, the marginal edges of all the pages will be uniform.

Mounted on the channel 23 carried by the framework of the table, are a plurality of combined sheet-stops and grippers 24, 24, two such devices being shown in the present instance, and each consisting of a frame formed of the side bars 25, 25, and the top plate 26 secured thereto by the rivets 27, 27, or other suitable means, said frame constituting a housing for the sheet-stop finger 28 and the sheet-gripping finger 29, which are pivotally mounted therein by the stud 30. By means of the spring 31 or other resilient member the sheet-stop finger 28 is normally held in contact with the table and the sheet-gripping finger 29 held above the same, a cam lever 32 pivotally mounted on the plate 26 by the stud 33 serving to depress the finger 29 so that the outer end thereof will clamp the sheet to the transparent top.

Depending from the forward ends of said side bars and attached thereto by the rivets 34, 34 is a flange 34' which co-operates with the under side of said channel 23. A plate

35 of spring material is attached to the rear of said frame by the screws 35' and the lower portion of said plate which extends below the side bars constitutes a means for holding the said frame resiliently against the rear of the channel 23. In the present instance the said plate is slit as indicated at 35'', 35''' and the end portions thereof below the slits are bent outwardly as indicated at dotted lines at 35''' (Fig. 8), the said bent portions taking against the rearward edge of the channel 23.

The side gage 36 is also mounted for movement longitudinally of said channel 15 and comprises the finger 37 pivoted at 38 to the arm 39, which in turn is swivelled by the stud 40 and screw 41 to the plate 42, to the under side of which the flange 43 is attached by the screw 44, a plate spring 44'

20 maintaining said plate in engagement with said channel. The spring 45 co-operating with one side of the arm 39 and having its free end arranged against a shoulder 46 maintains said arm in such position that 25 the side gage 37 is normal to the line 47 connecting the outer ends of the sheet-stops, and the said spring limits the movement of said plate in a counter-clockwise direction while permitting the same to be turned 30 about the stud 40 in the opposite direction. Preferably a plate spring 48 attached to the member 39 is employed to maintain the finger 37 in contact with the transparent top 21.

35 It will be noted that the combined sheet-stops and grippers and also the side gage are movable longitudinally of the table and that each is accurately positioned on the channel 23 and is held in resilient engagement therewith. The rear end of the arm 39 is provided with a pointer 39' co-operating with the scale 39''.

The alining bar 49 is arranged parallel to the line 47 connecting the forward ends 45 of the sheet-stops 28, 28 and is provided with means whereby it may be moved transversely of the table, such means being shown in the present instance as gears 50, 50 meshing with the parallel racks 51, 51, said gears being rigidly connected to the shaft 52 journaled in the blocks 53, 53 and in the hand-piece 54 mounted on said alining bar. One end of said alining bar is provided with a pointer 55 arranged to travel over the scale 56.

Obviously the racks and pinions 51, 50 will maintain the straight edge in parallelism with the line 47.

In order to place the straight edge on the 60 proof sheet without crumpling the edge thereof, it is desirable to elevate said straight edge slightly above the top 21 before moving the same over the sheet. In the present instance I so arrange matters that the movement of said alining bar at

right angles to its direction of movement across the table will serve slightly to elevate said bar.

While various means may be employed for this purpose, I prefer to employ a cam 70 arrangement consisting, as shown, in the upright 57 having a bevelled edge 58 arranged to co-operate with the reversely bevelled edge 59 formed on the guide member 60, the latter being secured to the block 53 by the bracket 61. At the opposite end of said alining bar is a somewhat similar bracket 62 carrying a cam arranged to co-operate with a stationary member to elevate that end of the alining bar, the same distance as 80 the end first mentioned, and it will be noted that such elevation of said bar is effected without disengaging the pinions from their respective racks.

Arranged at right angles to the bar 49 is 85 a bar 63 provided with a hand-piece 64 and gears 65, 65 rigidly attached to the shaft 66 journaled in the bearings 67, 67 and in said hand-piece, said gears meshing with the racks 68, 68, whereby said alining bar may 90 be moved longitudinally of said table without altering its angular relation to the bar 49. Depending from the journals 67 are brackets 69 carrying flanges 70, the under 95 surface of which is bevelled, as shown at 71, and co-operates with the cam surface 72 so that the movement of said alining bar at right angles to its direction of movement across the table will elevate said bar without 100 disengaging the pinions 65 from their racks 68. A pointer 67', attached to the journal 67, is arranged to travel over the scale 39''.

It is to be understood of course that the cam arrangement employed at the right-hand end of the bar 63 is similar to that shown and already described in connection with the righthand end of the bar 49, and also that the cam members at the lefthand end of the bar 49 are similar to those shown at the lefthand end of the bar 63.

In the use of my improved line-up table a 110 proof-sheet 73 (see Fig. 5) is placed on the table, and its lefthand end alined against the side guide 36, as indicated by the dotted line 74. The forward end thereof is positioned by the sheet-stops 28, 28 which are normally down against the table, and then the sheet is clamped in position by the cam levers 32 which force the gripping fingers 29 firmly against the sheet. The alining bars are then moved across the sheet to determine the alinement of the units printed thereon.

In the lining-up operation, it is sometimes 125 desirable to rule straight lines on the proof sheet along the edge of the alining bars. While a variety of marking devices may be employed for this purpose, I prefer a marking device mounted on and slidable along each straight edge, such device being shown 130

at 75 and consisting of a suitable carriage provided with wheels 76, 76 mounted to travel on the track 77 which is secured to the alining bar. A flange 78, spring-connected, 5 as indicated at 79, with the carriage, cooperates with a guideway in said track to prevent the carriage from leaving the same. The forward side of the carriage is provided with a dove-tailed guideway for receiving 10 the marker holder 79'. The particular form of marker shown in Figs. 10, 11 and 12 consists of a bevelled wheel 80 of carbon or other suitable marking material rotatably connected to the marker holder by the 15 screw 81. Within the recess housing the upper portion of the marker wheel is a bevelled scraper 82 maintained against said marker by the spring 83 whereby the edge of the marking wheel is always maintained sharp and pointed. 20

By means of the screw 84 threaded to the carriage and also to the marker holder 79 and provided with the knurled head 84', the vertical position of the marking wheel may 25 be varied in a manner that will be obvious, longitudinal movement of said screw being prevented by the top plate 79" and the collar 79".

An alternative form of marking device 30 employing an ink reservoir 85 and an inking wheel 86 is shown in Figs. 13 and 14, the ink being supplied to the wheel by the roller 87 geared to the said wheel by the gears 88, 88 and receiving its supply of ink 35 by contact with the roller 89.

Having thus described illustrative embodiments of my invention, without however limiting the same thereto, what I claim and desire to secure by Letters Patent is:—

40 1. A printer's line-up table comprising in combination a transparent top, illuminating means disposed beneath said top, lever actuated sheet-stops and grippers arranged at the forward edge of said table, an alining bar disposed parallel to a line connecting the forward ends of said stops, an alining bar disposed at right angles to the bar first mentioned, and means whereby said bars, respectively, may be moved transversely and longitudinally of said table without change in their angular relation.

45 2. In a printer's line-up table, a combined sheet-stop and gripper comprising a frame, means connecting said frame relatively to said table for movement in one direction, two fingers pivotally mounted in said frame, resilient means normally holding the end of one of said fingers in contact with said table and the end of the other of said fingers upwardly therefrom, and lever-operated means for depressing the last mentioned finger.

50 3. In a printer's line-up table, an alining bar, means connecting said bar relatively to said table for movement in one direction, said means also permitting movement of

said bar at right angles to said direction, and means whereby the movement of the bar at right angles to the first-mentioned direction of movement with respect to said table will elevate said bar above said table. 70

4. In a printer's line-up table, an alining bar, means connecting said bar relatively to said table for movement in one direction, a marking device mounted for movement longitudinally of said alining bar, and means 75 for adjusting said marking device vertically.

5. A printer's line-up table comprising in combination a transparent top, illuminating means arranged beneath said top, sheet-stops arranged at the forward edge of said table, an aligning bar disposed parallel to a line connecting the forward ends of said stops, means connecting said bar relatively to said table for movement in one direction, 80 racks arranged in parallel relation on opposite sides of said top, and pinions associated with said bar and engaging said racks. 85

6. A printer's line-up table comprising in combination a transparent top, illuminating means disposed beneath said top, sheet-stops arranged at the forward edge of said table, an aligning bar disposed parallel to a line connecting the forward ends of said stops, 90 an aligning bar disposed at right angles to the first mentioned bar, means connecting one of said aligning bars respectively to said table for movement in one direction, means connecting the other of said aligning bars 95 relatively to said table for movement in the direction at right angles to that of the first mentioned aligning bar, a pair of racks mounted on opposite sides of said tops, a second pair of racks mounted on the opposite ends of said tops, and pinions associated with said bars, respectively, and each engaging one of said pairs of racks. 100

7. In a printer's line-up table, an aligning bar, means connecting said bar relatively to said table for movement in one direction, said means also permitting movement of said bar at right angles to said direction, a pair of racks disposed on the opposite edges 110 of said table, pinions associated with said aligning bar and engaging said racks and means whereby the movement of said bar at right angles to the first-mentioned direction of movement with respect to the table will elevate said bar above said table without 115 disengaging said pinions from said racks.

8. In a printer's line-up table, an aligning bar, means connecting said bar relatively to said table for movement in one direction, said means also permitting relative movement of said bar at right angles to said direction, cam surfaces secured, respectively, to the ends of said bar, and co-operating cam surfaces attached to said table whereby the movement of said bar in the direction of its 120 125 130

length will cause the cam surfaces attached to said bar to ride up over the cam surfaces attached to said table.

9. In a printer's line-up table, a side gage support, means connecting said support relatively to said table for movement in one direction, and a side gage swivelled to said support.

10. In a printer's line-up table, a side gage support, means connecting said support relatively to said table for movement in one direction, a side gage pivotally connected to said support and a resilient member co-operating with said support and said gage whereby said gage is normally maintained in operative position and may be rotated with respect to its support to, and held in, inoperative position.

11. In a printer's line-up table, an aligning bar, means connecting said bar relatively

to said table for movement in one direction, a pair of racks disposed on the opposite edges of said table, pinions associated with said aligning bar and engaging said racks, and means whereby said bar may be elevated above said table without disengaging said pinions from said racks. 25

12. In a printer's line-up table an aligning bar, means connecting said bar relatively to said table for movement in one direction, 30 a pair of racks disposed on the opposite edges of said table, pinions associated with said aligning bar and engaging said racks, and cams for elevating said bar above said table without disengaging said pinions from 35 said racks.

In testimony whereof I have affixed my signature.

JAMES WEST.
